FIREPROOF BUILDING CONSTRUCTION

Bruno E. Balduf, Chicago, Ill., assignor to United States Gypsum Company, Chicago, Ill., a corporation of Illinois

Application July 3, 1935, Serial No. 29,592

10 Claims. (Cl. 72—46)

This invention relates to building constructions, and has reference more particularly to building constructions in which metal studs and framework are used to support composition boards.

In the construction of "dry wall" partitions, floors and ceilings, it is desirable to attach composition boards, such as gypsum or fiber boards, directly to steel studs and framework of a building. Methods and means for accomplishing this end previously proposed, have been found to be laborious in field erection and the units have been expensive to construct in the factory. It is also desirable to provide a frame construction suitable for use in the outside walls of buildings.

An object of this invention therefore, is to provide a building construction utilizing composition boards directly attached to metal studs and framework of a building.

Another object of the invention is to provide a construction of the class described which may be easily and cheaply constructed in the factory and erected in the field with a low labor cost.

A further object of the invention is to provide a steel frame construction suitable for forming the outside walls of buildings; also to improve building constructions in other respects hereinafter specified and claimed.

Reference is to be had to the accompanying drawings forming a part of this specification, in which

Fig. 1 is a perspective elevation of my improved partition structure,

Fig. 2 is a sectional plan view through the partition taken on line 2—2 of Fig. 1,

Fig. 3 is a sectional plan view at the junction of a partition and intersecting wall,

Fig. 4 is a sectional plan view of two intersecting partitions at the corner of a building,

Fig. 5 is a perspective view of a partition stud combined with an expansion member,

Fig. 6 is a sectional plan view through the stud taken on line 6—6 of Fig. 5,

Fig. 7 is a sectional plan view taken on line 7—7 of Fig. 1 showing the manner of attaching the studs to supporting runners,

Fig. 8 is a sectional perspective view showing joists in a building construction, and

Fig. 9 is a sectional plan view through a modified form of partition structure.

Referring to the drawings by numerals, my improved studs comprise a pair of channels 10 in spaced parallel relation, said channels including webs 11 and outstanding flanges 12 in opposed relation. Perforated connector plates 13 are

secured in pairs to opposite sides of the channels 10, said plates being secured, as by spot welding to the flanges 12. The plates 13 are provided with closely spaced perforations 14 which are arranged to engage board attaching screws 15 which secure composition boards 16 of gypsum, fiber or the like in face abutting relation against the plates 13. In securing the boards 16 to the plates 13, the boards are placed against the plates and a straight punch is pushed through the board, 10 the point of the punch entering the nearest hole 14. The punch is then withdrawn and the screw inserted in the hole and tightened to draw the board tightly against the plate 13. If abutting edges of the board lie opposite the stud channels 10, they are attached in the manner above described, the joint is filled with a cementitious joint filler, and the exposed surfaces of the boards are decorated with plastic paint, wall paper or the like. It will be seen that boards 16 do not touch the stud flanges 12 between the plates 13 and are free to vibrate under sound waves impinging against the wall face. The partition thus acts as a membrane and has a high acoustical or sound absorbing value, especially 25 for sound waves of low frequency. The partition also exhibits marked sound insulating value.

The tops of channels 10 are seated between flanges 18 of channel runners 19, said flanges being connected by webs 20 which are provided with spaced perforations 21 for nailing attachment to the ceiling of a room, or other building framework. A similar bottom runner 22 with web 23 and flanges 24 receives the bottom ends of channels 10. In order to lock the stud channels 10 in place, runner flanges 18 and 24 are bent inwardly at the time of erection between said channels 10 to form locking detents 25 (Fig. 7). Runner flanges 18 and 24 are provided at intervals with a plurality of spaced perforations 26 to receive the board attaching screws 15. 30 35 40

In some cases, it is desirable to provide an extension member 28 at the top of the stud in order to accommodate varying ceiling heights. This extension member is preferably U-shaped and 45 includes channel legs 29 having flanges 30, said flanges being cut out for clearance to permit bending so as to form the connecting channel member 31. Perforated plates 32 are secured between the inside of flanges 30 by spot welding or riveting, so as to give clearance past the perforated plates 13. The board attaching screws 15 engage in the perforations in plates 32 and the boards then hold the extensions 28 in the desired adjusted position. The channel legs 29 fit 50 55

snugly but slidably between the channel webs 11 before the assembly of boards 16 so that said extension members may be readily moved to give the desired length to the stud. Connector strips 32a are secured to the bottoms of flanges 30 to make sliding connection with the stud flanges 12. The detents 25 are pressed about the tops of extension members 28 as above described in order to hold the tops of said extension members in 10 position.

In assembling intersecting partitions as illustrated in Fig. 3, and in forming corners of rooms as illustrated in Fig. 4, runners identical with runners 19 and 22 and having channel webs 14, 15 are attached to perforated plates 13 by screws 35 which pass through boards 16 and engage in the perforations in the plates 13. Outstanding flanges 36 formed on the channel web 34 extend at right angles to the boards 16 and are perforated to receive screws 37 for attaching boards 38 to said flanges 36. In order to provide framing for doors 40 and windows, (Fig. 4) wooden strips 41 are secured between channel flanges 12 by screws 42 engaging in drilled holes in the web 11. Suitable door jambs 43 and trim 44 may then be attached to the strip 41 by nailing. Channel studs 10 may be made of heavier construction (Fig. 8) and placed in a horizontal position to form girders and joists, ceiling boards 30 46 and floor boards 47 being then attached to the perforated plates 13 by screws in the manner previously described.

In the modified form of construction shown in Fig. 9, stud channels 50 have outstanding flanges 51 which are secured together by perforated plates 52. These plates 52 have center sections 53 which are bowed inwardly between the stud channels 50 and each plate is provided with one or more pressed integral stiffening ribs 54 to hold 40 said plates in shape against the pressure of board attaching screws 55 which engage in the perforations in said plates. Boards 56 made of fiber and being of semi-flexible nature, are secured to the plates 53 by screws 55, and are arranged 45 in edge abutting relation adjacent the plates 53. The pressure of the screws bends the edges of boards 56 slightly inwardly to form a face cavity 57 so that the joint may be leveled off with cementitious material 58 and plastic paint to form 50 a strong, reinforced joint due to the excess cementitious material at the joint.

I would state in conclusion that while the illustrated examples constitute practical embodiments of my invention, I do not wish to limit 55 myself precisely to these details, since manifestly the same may be considerably varied without departing from the spirit of the invention as defined in the appended claims.

Having thus described my invention, I claim 60 as new and desire to secure by Letters Patent:—

1. A building element, comprising a pair of metallic channels with the webs thereof in spaced, parallel relation, the flanges of said channels lying in spaced, parallel planes, and foraminous plates secured to said flanges, said plates having closely spaced perforations adapted to receive board attaching screws.

2. A building element, comprising a pair of metallic strips in spaced, parallel relation, and a 70 plurality of foraminous plates rigidly secured to opposite sides of said strips to secure said strips together in spaced relation, said plates being provided with closely spaced perforations adapted to receive board attaching screws.

3. A building element, comprising a pair of

elongated strips in spaced, parallel relation, and a foraminous plate secured at opposite edges to said strips so as to rigidly connect said strips, said plate being provided with closely spaced perforations adapted to receive board attaching 5 screws.

4. A building stud, comprising a pair of elongated strips in spaced, parallel relation, a plurality of perforated plates connecting said strips, said plates having closely spaced perforations for 10 receiving board attaching screws, an extension member slidably received between said strips and carrying a perforated plate, and means for securing said extension member in adjusted position to provide a stud of desired length. 15

5. In a building construction, a plurality of structural elements each comprising a pair of spaced, parallel strips of material connected by a series of perforated plates having a multiplicity of closely spaced perforations, flat facing elements 20 adjacent said perforated plates, and screws passing through said facing elements and engaging in the perforations in said plates.

6. In a building construction, a plurality of structural elements arranged in a plane in spaced, 25 parallel relation, each of said elements comprising a pair of metallic channels with parallel webs and flanges extending from the edges of said webs, a plurality of perforated plates secured to said flanges and connecting said channels, said 30 plates having a multiplicity of closely spaced perforations, flat facing elements adjacent said perforated plates, and screws passing through said facing elements and engaging in the perforations in said plates. 35

7. In a building construction, a structural element comprising a pair of metallic channels with parallel webs and flanges extending from the edges of said webs, a plurality of perforated plates secured to said flanges and connecting said channels, said plates having a multiplicity of closely spaced perforations, flat facing elements adjacent 40 said perforated plates, screws passing through said facing elements and engaging in the perforations in said plates, a metallic wall channel having a web abutting against a facing element adjacent said perforated plates, said wall channel having outstanding flanges, screws passing through said wall channel web and said facing elements and engaging in the perforations in said perforated plate, and intersecting facing elements 45 secured to the outstanding flanges of said wall channel.

8. In a building construction, a pair of spaced, parallel strips of material, a plurality of perforated plates secured to each side of said strips to rigidly secure said strips together, said plates being bowed inwardly between said strips and having a plurality of closely spaced perforations, a pair of flat facing elements having abutting 60 edges adjacent said perforated plates, screws passing through said facing elements and engaging in the perforations in said plates so as to bend the edges of said facing elements inwardly to follow the contour of said bowed plate and form a 65 cavity on the exposed faces of said facing elements adjacent the abutting edges thereof, and cementitious material covering the exposed faces of said facing elements and filling said cavity.

9. In a building construction, a plurality of 70 structural elements arranged in a plane in spaced, parallel relation, each of said elements comprising a pair of elongated strips of material in spaced, parallel relation, perforated plates secured to said strips and forming a rigid connection there- 75

between, said plates having closely spaced perforations, flat facing elements adjacent said perforated plates and secured thereto by screws, and a supporting channel engaging each end of said strips so as to secure said strips to a building frame.

10. In a building construction, a building stud comprising a pair of elongated strips in spaced, parallel relation, a plurality of foraminous plates secured at opposite edges to said strips so as to

rigidly connect said strips, said plates being provided with closely spaced perforations, and building boards supported in face abutting relation against said plates and secured thereto by screws, said boards being out of contact with said strips 5 between said plates so as to provide semi-flexible membranes for the acoustical absorption of sound and for sound insulation.

BRUNO E. BALDUF. 10
